UNITED STATES PATENT OFFICE

MARTIN E. FITZ GERALD, OF DANVILLE, ILLINOIS, ASSIGNOR TO UNIVERSAL DRAFT GEAR ATTACHMENT COMPANY, A CORPORATION OF ILLINOIS

CAR JOURNAL PROTECTOR

Application filed October 5, 1931. Serial No. 586,946.

The invention relates to a device for protecting the journals of railway car axles from injury, particularly during the process of assembling and disassembling them with and from the journal boxes. In the operations of assembling and disassembling, journals are in danger of being marred or scratched and this danger is greatly increased since the practice of casting the boxes integrally with the truck frames has come into use.

When it becomes necessary to remove a pair of wheels from the car, the wedges and bearing brasses are first withdrawn from the box and the latter is drawn forward over the journal.

The box being of considerable weight there is great danger that some part of it, and particularly the dust guard contained within it, shall come into contact with the journal. The journal being highly polished and made of soft steel is easily marred or scratched. When the box is formed integrally with the truck frame, the casting weighs approximately 600 lbs. and is difficult to handle without injury to the journal.

When the journal surface is marred or scratched, even though the injury may be so slight that it escapes notice, the conditions are created for developing a hot box as soon as the car comes into service.

Such injuries to the journal are still more liable to occur in the assembling operation than in disassembling and are not apt to be noticed or reported by the workmen. When the car comes into service with an abraded journal, fibers of the packing waste are caught and carried under the brass where they may lodge and set up sufficient friction to ignite the lubrication. Unless the heating is quickly discovered, and it is quite likely to escape notice—especially on freight trains—the journal may be, and often is, melted off and a serious accident results.

The object of the present invention is to provide means for protecting the journal from abrasion during the operations of assembling it with or disassembling it from the box.

A preferred embodiment of the invention is hereinafter described and is illus-

trated in the accompanying drawing, in which

Figs. 1 and 2 are, respectively, plan and side views of the protector applied to a car journal;

Fig. 3 is a sectional view on the line 3—3 of Fig. 2;

Fig. 4 is a view in perspective of the improved protector.

There is shown at 10 a portion of a car axle, 60 its journal being represented at 11 and the brass retaining flanges at the ends of the journal being shown at 12 and 13. In practice, as is well-known, the journal projects into a so-called journal box from the rear 65 end of the latter. The box is attached to or formed integrally with the end frame of the truck and its weight is borne by the journal 11, there being interposed between the journal and the top of the box a bearing block known 70 as a brass which rides upon the journal and a retaining wedge placed in between the brass and the top of the box for retaining the brass in position and preventing it from turning with the journal. The lower portion of the 75 box chamber is packed with cotton waste which is saturated with oil. A dust guard of metal is fitted within the upper portion of the rear end of the box and rides upon the end of the axle 10 immediately back of the inner 80 journal shoulder 13.

The improved protector is formed of a sheet of metal 14 of sufficient length to fit between the flange 12 and shoulder 13 and is curved as shown in Fig. 4 to conform to the 85 circumference of the journal 11 and covers the upper half thereof. The ends of the plate 14 may be flanged upwardly, such a flange 15 being shown at its rearward end for engaging the shoulder 13. The side margins of the plate 14 are preferably outwardly flanged as shown at 16 and a pair of spring arms 17 are attached to the outer face of the plate 14 adjacent its side margins by rivets or other suitable fastening means. The arms 90 are offset at 18 to accommodate the journal flange and are joined at their forward ends by an integral handle partition 19. The spring arms 17 are so spaced from each other and shaped as to clamp tightly against the flange 100

when the protector is seated on the journal and the protector is thus prevented from turning movement as work of assembling or detaching proceeds. The side flanges 16 of 5 the protector guard the journal against accidental contact with it of tools which may be used by the workmen. In use in disassembling, the protector is inserted after the brass has been removed, and in assembling, is fitted 10 upon the journal before it is inserted into the box and is readily withdrawn from the open front end of the box after the latter has been properly positioned over the journal.

While the form of structure disclosed has 15 been found to be highly practicable, the invention is of sufficient scope to include any form of structure adapted to cover the journal and being provided with means for preventing its displacement, as by turning about 20 the smooth surface of the journal.

What I claim, therefore, is:

1. In a car journal protector, a sheet metal plate conforming in length with the journal and curved transversely and spring arms 25 projecting from the end of the plate and adapted to frictionally engage the end flange of the axle.
2. In a car journal protector, a sheet metal plate conforming in length with the journal and curved transversely and spring arms 30 projecting from the end of the plate and adapted to frictionally engage the end flange of the axle and a handle connecting the outer ends of the arms.
3. In a car journal protector, a sheet metal plate conforming in length with the journal and curved transversely and a pair of clamping 35 springs projecting forwardly from the plate adjacent to its side margins for engaging the end flange of the axle.

In testimony whereof I affix my signature.

MARTIN E. FITZ GERALD.
